(57) **CLAIM**

The ornamental design for a vest with reflective side panels,
as shown and described.

DESCRIPTION

FIG. 1 is a front perspective view of a vest with reflective side panels incorporating our new design;

FIG. 2 is a bottom perspective view thereof;

FIG. 3 is a top plan view thereof; and

FIG. 4 is a bottom plan view thereof.

FIG. 5 is a left side view thereof;

FIG. 6 is a front view thereof; and,

FIG. 7 is a rear view thereof.

The broken lines shown in the drawings illustrate portions of
the vest with reflective side panels that form no part of the
claimed invention.

The solid lines form a perimeter around the reflective side
panels.
